(57) CLAIM

The ornamental design display and processing unit for a medical scanning device, as shown and described.

DESCRIPTION

FIG. 1 is a top perspective view of a display and processing unit for a medical scanning device showing my design;

FIG. 2 is a top plan view thereof;

FIG. 3 is a left side elevational view thereof;

FIG. 4 is a bottom plan view thereof;

FIG. 5 is a right side elevational view thereof; and,

FIG. 6 is a front plan view thereof.

The broken lines are included for the purpose of illustrating portions of the display and processing unit for a medical scanning device that forms no part of the claimed design. The cord is shown broken away in order to indicate that a specific length of the cord forms no part of the claimed design.
